CLAIM

The ornamental design for a vehicle recharging station, as shown and described.

DESCRIPTION

1. Vehicle recharging station

1.1 is a rear view;

1.2 is a bottom view;

1.3 is a front view;

1.4 is a side view;

1.5 is a front perspective view;

1.6 is a side view; and

1.7 is a top view.

In the reproductions, the broken lines are for the purpose of illustrating environment only and form no part of the claimed design.
